CLAIM

I claim the ornamental design for a gimbal shroud for a security camera, as shown and described.

DESCRIPTION

FIG. 1 is a perspective view of a gimbal shroud, wherein the broken lines illustrate environment structure that is not part of the design;

FIG. 2 is a rear elevation view of the gimbal shroud of FIG. 1, wherein the broken lines illustrate environment structure that is not part of the design;

FIG. 3 is a bottom plan view of the gimbal shroud of FIG. 1, wherein the broken lines illustrate environment structure that is not part of the design;

FIG. 4 is a left side elevation view of the gimbal shroud of FIG. 1;

FIG. 5 is a right side elevation view of the gimbal shroud of FIG. 1, wherein the broken lines illustrate environment structure that is not part of the design;

FIG. 6 is a top plan view of the gimbal shroud of FIG. 1, wherein the broken lines illustrate environment structure that is not part of the design;

FIG. 7 is a front elevation view of the gimbal shroud of FIG. 1; and,

FIG. 8 is a perspective view of the gimbal shroud of FIG. 1, wherein the broken lines illustrate environment structure, associated with a gimbal surrounded in part by the gimbal shroud and a trim ring and dome that surround the gimbal shroud, that is not part of the design.

The design is the visual features of a gimbal shroud shown in solid lines in the drawings.
